UNITED STATES PATENT OFFICE.

FERDINAND G. GASCHE, OF CHICAGO, ILLINOIS.

MACHINE FOR PERFECTING INGOTS.

1,389,300.

Specification of Letters Patent. Patented Aug. 30, 1921.

Application filed July 17, 1917. Serial No. 181,006.

To all whom it may concern:

Be it known that I, FERDINAND G. GASCHE, a citizen of the United States and resident of Chicago, Cook county, Illinois, have invented a certain new, useful, and Improved Machine for Perfecting Ingots, of which the following is a specification.

My invention relates generally to ingot perfecting machines, which operate laterally 10 to compress the ingot for the purpose of expelling the impurities, consolidating the ingot, and otherwise perfecting it.

My invention, while usable elsewhere, is primarily intended for employment in the 15 steel industry and for that reason will be described with particular reference thereto.

The steel ingots are poured and cast in molds, which are mounted upon buggies or carriages, and when the ingots have sufficiently solidified to maintain their shape, 20 the molds are stripped from the ingots, and their supporting buggies are moved along from the stripping position to the position or house where they are squeezed. In commercial practice these ingots and their buggies are in relatively close or compact relation, particularly is this so with the relatively smaller ingots and other pieces. It 25 is desirable that the structure or mechanism for squeezing or perfecting the ingots shall be portable to the end that that ingot or other piece in the condition best suited for the squeezing operation may be selected and 30 acted upon; and to the further end that it shall not be necessary to stop the carriage or buggy containing the ingot, or other piece, accurately at any definite point.

The general object of my invention is to 35 provide an ingot perfecting mechanism wherewith relatively compactly or closely associated ingots and other pieces can be operated upon expeditiously.

A further object of my invention is to 40 provide an ingot-perfecting mechanism, where- 45 with the manipulation of the valves, levers and other parts necessary to the proper and convenient control of the mechanism may be operated from one side of the train or series of ingots or from the leverman's cage 50 on the traveling crane, which is generally employed in acting upon the ingot or other piece. In the accomplishment of the above noted objects, and others, I have devised a type of ingot compressing mechanism, one 55 of the leading advantages of which is a tandem arrangement of main compressor pis-

ton, and associated pull-back pistons mounted upon tension rods connecting the squeezing jaws of the machine.

To facilitate the various movements required of the clamps and jaws in view, of the limited space, and the need of easy accessibility, I have devised a binary system fluid-control for governing the motion of the several pistons. I also reduce the bulk 60 of the machine, *i. e.*, enhance its compactness by making the clamps or jaws of sufficiently rigid construction to withstand the pressures exerted upon the ingots without relying principally upon cross-heads or 65 yokes for that purpose. As the ingots in practice will have variations of their surfaces, and may assume angular positions, I provide the clamps or jaws with suitable cylindric bearing plates which permit slight 70 rotation of the clamps or jaws in a vertical plane, thus automatically adapting the ingot engaging surfaces of the clamps to the accidental variations of the surfaces of the ingots, and making the quick and easy treatment 75 of the ingot possible.

Further objects and advantages of my invention will appear hereinafter, and my invention will be better understood by reference to the accompanying drawings, which 80 illustrate that form of my invention which I have so far found best adapted to the accomplishment of the objects in view.

In said drawings:

Figure 1 is a small, vertical sectional view 90 of the squeezer house, showing the squeezer suspended therein from the overhead traveling crane;—Fig. 2 is an enlarged plan view of the ingot squeezer mechanism, and ingot 95 of Fig. 1, a portion of the mechanism being broken away better to disclose the interior construction;—Fig. 3 is a view substantially on the line 3—3 of Fig. 2 of the ingot mounted upon its buggy, and showing the ingot 100 perfecting or squeezer mechanism encompassing the ingot;—and Fig. 4 is a somewhat diagrammatic sectional view illustrating the fluid control mechanism whereby the jaws or clamps of the squeezer may be manipulated as desired.

As indicated in Fig. 1, the squeezer house or building, is equipped with a traveling crane, 4, which may be moved longitudinally over the tracks, in usual manner, and bears the trolley, 5, which is transversely movable. 105 The operator is carried in the cage 6, and from thence controls the movements of the

trolley, 5, and of the hoisting machine, 7, thereon. The stripped ingot, A, is shown on its car or buggy, B. Above it, and suspended from the crane trolley, is the squeezer, C, which obviously may be raised and moved both longitudinally and transversely by means of the traveling crane. The squeezer, C, as will be presently explained, in detail, is essentially two normally open jaws, together defining an opening large enough to admit the upright ingot. Upon the arrival of the ingot in the squeezer house the open squeezer is first positioned directly above the ingot and then lowered until the top of the ingot appears through the squeezer. Thereupon power is applied to close the squeezer jaws upon and thereby compress the ingot. This statement is made to the end that the general operations of treating the ingot may be understood before proceeding to a detailed description of my novel mechanism which will be described under two general headings, to-wit, (1) squeezer proper, and (2) the squeezer controlling mechanism.

25   *The squeezer proper.*

My novel squeezer, though solid and heavy, is of compact and simple construction. It comprises spaced parallel tension rods, 30 12-12' upon the threaded ends, 13^a, of which are mounted adjustable clamp nuts, 13. 14-14' are the clamps or jaws of the machine, and have rigidly or integrally cast hubs, 15, surrounding the tension rods, 35 12-12'. A supporting surface, 16, at the inner extremity of the hubs is approximately the size of the tension rods, 12-12', and serves, by engagement with the rods 12-12', as a fulcrum for the clamps, 14-14', and 40 also as a fulcrum for the cylindric bearing member, 17-17'. The bearing members, 17-17', are rigidly attached to the clamps or jaws, 14-14', and have seating surfaces on the distance pieces, 19, under the clamp 45 nuts, 13, and on the cylinder frame, 20, at the operating side of the machine. In the operation of the squeezer it is necessary to exert powerful force to squeeze the ingot and then to provide means of separating or 50 freeing the jaws from the ingot to permit its removal and to enable the encompassing of another ingot. Since there are two sets of similar mechanisms, each associated with one of the tension rods, a detailed description 55 of one will serve for both.

To this end I provide a main cylinder, 21, an alined pull-back cylinder, 23, and an immediate or connecting head, 22. In the main cylinder, 21, I provide the main compressor 60 piston, 24, rigidly attached to the tension rod, while an extension, 25, of the tension rod provides a pull-back plunger or for the attachment of a piston if desired.

It will be understood that the cylindrical bearing members, 17-17', are suitably se-

cured to their respective jaws or clamps, 14-14', so as to move therewith when the jaws are actuated and that the jaws themselves are removable for removal, inspection or repair.

The mechanism, as thus described, may be operated under the requisite pressure by any medium, but the portable form of machine gives preference to use of liquids on the main plunger or piston, 24, and steam or air on the pull-back plunger or piston. Apparatus for accomplishing the operation of the squeezer is preferably mounted on the frame, 20, of the squeezer, although a part of the equipment, may be mounted on the traveling crane by which the squeezer is transported, as hereinbefore described.

The squeezer control mechanism.

The essentials of the squeezer control mechanism are best shown in the somewhat diagrammatic view (Fig. 4). Therein 30 is a compressed air drum or reservoir, receiving its supply of air through the pipe, 30', connected with an air compressor that 35 may be attached to the ingot squeezer frame or to the stage of the traveling crane. In special cases the flexible hose and pipe-connection from a stationary air compressor may be employed, although this will generally be limited to use where the squeezer does not operate at relatively great distances. 34 is a surge tank capable of withstanding fluid pressures approximating those which will apply to the reservoir, 30. 35 is a combination automatic check and positive relief valve, connected on its low pressure side to the surge tank, 34, by means of the closed pipe, 36. The high pressure side of the valve, 35, connects by the closed pipe, 37, to the plunger chamber, 38, of the fluid intensifier, D. Steam or air is admitted to either side, 39-39', of the piston 39", through the use of the control valve, 40, and the pipe, 41, connecting with the reservoir, 30. The plunger chamber, 38, also connects through the medium of the pipe, 42, with the interior of the main compression cylinder, 21. 54 is a control valve, somewhat resembling the valve, 40, of the fluid intensifier, but having a supply pipe, 55, from the reservoir, 30, and a connection, 56, to the upper portion of the surge tank, 34, as well as a connection, 57, to the interior of the pull-back cylinder, 23. Exhaust ports, 59-59', are shown for the valve, 54, which is of the type known as a piston valve, though any other suitable type of construction, capable of performing the same operations, may be employed.

Operation of the device.

In practical use, the spaces of the apparatus, consisting of a part of the surge tank, 34, of the pipe connections, 36, 35, 37 and 42, together with the plunger chamber, 38, 130

of the liquid intensifier, and of a part of the displacement of the main plunger cylinder, 21, are to be filled with water or other liquid. Spaces in the compression tank, 30, 5 upper part of the surge tank, 34, spaces 39, 39', of the intensifier cylinder, spaces 18 of the pull-back cylinder, and the connecting valves and fittings are filled with some elastic fluid under pressure, such, for example, 10 as steam or air, which is directed to the several compartments by means of the control valves, 40, and 54.

Suppose now an ingot has been treated in the compressing machine or squeezer, and it 15 is desired to prepare the latter for the reception of another ingot and to complete the operations thereon.

Fig. 3 shows the initial position of the jaws or clamps upon the ingot, the parts 20 12, 12', 24, and 25 are now at their extreme right-hand position. Air is admitted to the interior of the pull-back cylinder, 23, thus pushing outwardly the parts 12, 12', 24 and 25 with the left-hand clamp or jaw, 14, thus 25 providing the necessary intervening space for the insertion of the new ingot. This is accomplished by the control apparatus as follows:

Air is admitted to the pull-back cylinder, 23, by a left-hand movement of the piston valve, 54, which thereby enables the air to pass from the tank, 30, through pipe, 55, middle passage of the valve, 54, and through the pipe, 57, to the pull-back cylinder. At 35 the same time the left-hand movement of the piston valve, 54, makes an open air connection for the top of the surge tank, 34, through the pipe connection, 56, and the exhaust, 59'. The expansion of the air in the pull-back cylinder actuates the connected tension rod and the main compressor cylinder thereby forcing the liquid backward through connections, 42, 38, 37, 35 and 36 into the bottom of the surge tank, 34. It 45 will be understood that before this action occurs, the check valve, 35, is raised by the positive lever, 20^a, which may be controlled by hand, if desired. In case of accidentally large friction resistance against the moving 50 of the parts of the intensifier, the plunger in space, 38, thereof, is further assisted to its extremely inward position by the admission of air to the left side, 39, of the piston, 39'', the air passing from the cylinder, 30, through pipe, 41, and being properly directed by means of the piston-like valve, 40. By the automatic action of the check valve, 35, any additional supply of liquid from the surge tank that may be required by the 55 further displacement of the plunger in the chamber, 38, of the liquid intensifier, D, is insured. The valve, 54, is now moved to the right and admits air under pressure to the top of the surge tank, 34, through the 60 medium of the intermediate space of the

valve and the connecting pipes, 55 and 56, at the same time an open air connection is made with the interior of the pull-back cylinder, 23, by means of the connecting pipe, 57, and the exhaust port, 59. The pressure 70 in the surge tank, 34, will immediately cause the displacement of the liquid in the bottom of the surge tank and through the connections, 36, 35, 37, 38 and 42, to the interior of the main cylinder, 21, which obviously will 75 cause a movement of the main compressor piston, 24, and the tension rod to which it is connected. It will be understood that both cylinders operate simultaneously so that both tension rods are acted upon and 80 thus the clamps or jaws of the ingot compressor are forcibly brought into contact with the new ingot. Since the lever, 20^a, has not been released and the valve, 35, is on its seat conditions are such as to enable 85 the application of enormous pressures to the ingot. To this end valve, 40, is moved to right and compressed air or other elastic fluid is delivered to the right hand chamber 39' of the intensifier, through the medium of 90 pipe, 41, and control valve, 40. An open air connection is also made with the left hand side of chamber 39. The piston and plunger of the intensifier then move to the left causing very large hydrostatic pressures 95 on the main pistons of the ingot compressor or squeezer. A repetition of the motion of the intensifier plunger is possible with this arrangement, if unusual volume changes are to be imposed upon the ingot; 100 that is to say, the ingot may be subjected to successive compressions.

It should be noted that the controlling mechanism is arranged so that it may be operated from one side of the machine, and 105 that the parts are compactly arranged, thereby enabling the convenient and easy operation upon relatively closely associated ingots.

Since this disclosure will suggest to others 110 modified constructions whereby the substantial objects and purposes of my invention may be attained, I do not wish to be limited to the specific construction, or arrangement of the parts shown and described except 115 only as may be necessary by limitations in the hereunto appended claims.

I claim:—

1. The herein described improvements in machines for perfecting ingots, comprising 120 in combination a plurality of jaws, a tension rod upon which the jaws are mounted, and a piston directly connected to the tension rod.

2. The herein described improvements in 125 machines for perfecting ingots comprising in combination a plurality of jaws, a plurality of tension rods upon which the jaws are mounted, and pistons directly connected to the tension rods.

3. The herein described improvements in machines for perfecting ingots, comprising in combination a plurality of jaws, a tension rod upon which the jaws are mounted, 5 and main compressor and pull back pistons directly secured to the tension rod.

4. The herein described improvements in machines for perfecting ingots, comprising in combination a plurality of jaws, a plurality of tension rods upon which the jaws are mounted, and main compressor pistons 10 and pull back pistons directly secured to the tension rods.

5. The herein described improvements in machines for perfecting ingots, comprising in combination jaws, a tension rod upon 15 which the jaws are mounted, and a main compressor piston and a pull-back piston arranged upon the tension rod in tandem 20 relation.

6. The herein described improvements in machines for perfecting ingots, comprising in combination a plurality of jaws, a tension rod upon which the jaws are mounted, 25 a compressor piston directly connected to the tension rod, and means for moving the compressor piston in one direction.

7. The herein described improvements in machines for perfecting ingots, comprising 30 in combination a plurality of jaws, a tension rod upon which the jaws are mounted, a compressor piston directly connected to the tension rod, means for moving the compressor piston in one direction, and other 35 means for returning the main compressor piston.

8. The herein described improvements in machines for perfecting ingots, comprising in combination a plurality of jaws, a tension rod upon which the jaws are mounted; 40 a compressor piston directly connected to the tension rod, and valve controlled means for moving the compressor piston in one direction.

45 9. The herein described improvements in machines for perfecting ingots, comprising in combination spaced jaws, means operable by a fluid under pressure for causing relative movement of the jaws, a body of fluid 50 under pressure, an intensifier, a connection between the body of fluid, intensifier and fluid operable means, said connection communicating pressure of the body of fluid and of the intensifier to said fluid operable means, 55 said intensifier comprising a piston actuated plunger, and a valve for admitting a medium under pressure upon either side of the piston, a fluid pressure tank, and a connection between the fluid pressure tank and the 60 intensifier valve.

10. The herein described improvements in machines for perfecting ingots, comprising in combination spaced jaws, means operable 65 by a fluid under pressure for causing relative movement of the jaws, a body of fluid

under pressure, an intensifier, a connection between the body of fluid, intensifier and fluid operable means, said connection communicating pressure of the body of fluid and of the intensifier to the fluid operable 70 means, said intensifier comprising a piston actuated plunger, a valve for admitting a medium under pressure upon either side of the piston, a second fluid pressure tank, a connection between the second fluid pressure tank and the intensifier valve, and a connection between the second pressure tank and said body of fluid under pressure.

11. The herein described improvements in machines for perfecting ingots, comprising 80 spaced jaws, a main pressure cylinder, a pull back cylinder, a surge tank, an intensifier, a connection between the surge tank and intensifier, and between the intensifier and main pressure cylinder, a tank for fluid 85 under pressure, and means for directing said fluid under pressure to the intensifier and to the pull-back cylinder as desired.

12. The herein described improvements in machines for perfecting ingots, comprising 90 spaced jaws, a main pressure cylinder, a pull back cylinder, a surge tank, an intensifier, a connection between the surge tank and intensifier, and between the intensifier and main pressure cylinder, a tank for fluid 95 under pressure, and means for directing said fluid under pressure to the intensifier and to the pull-back cylinder and surge tank, as desired.

13. The herein described improvements in 100 machines for perfecting ingots, comprising spaced jaws, a main pressure cylinder, a pull-back cylinder, a surge tank, an intensifier, a connection between the surge tank and intensifier, and between the intensifier 105 and main cylinder, a tank for fluid under pressure, means for directing said fluid under pressure to the intensifier and to the pull-back cylinder as desired, and means for exhausting the fluid from the pull back cylinder. 110

14. The herein described improvements in machines for perfecting ingots, comprising spaced jaws, a main pressure cylinder, a pull-back cylinder, a surge tank, an intensifier, a connection between the surge tank and intensifier, and between the intensifier and main pressure cylinder, a tank for fluid under pressure, means for directing said fluid 120 under pressure to the intensifier and to the pull-back cylinder as desired, and means for exhausting the fluid from the surge tank.

15. The herein described improvements in machines for perfecting ingots, comprising 125 spaced jaws, a main pressure cylinder, a pull back cylinder, a surge tank, an intensifier, a connection between the surge tank and intensifier, and between the intensifier and main pressure cylinder, a tank for fluid under pressure, means for directing said 130

fluid under pressure to the intensifier and to the pull-back cylinder as desired, and means for exhausting the fluid from the surge tank and from the pull-back cylinder.

5 16. The herein described improvements in machines for perfecting ingots, comprising spaced jaws, main and pull back cylinders, a surge tank, a valve-controlled intensifier, a valve for the pull-back cylinder, and a fluid

10 pressure reservoir, a connection for liquid between the surge tank and main cylinder, a connection between the fluid pressure reservoir and the intensifier valve, and a connection between the pressure reservoir and

15 surge tank through the pull-back cylinder valve.

17. The herein described improvements in machines for perfecting ingots, comprising main and pull-back cylinders, a surge tank, a valve-controlled intensifier, a valve for the 20 pull-back cylinder, and a fluid pressure reservoir, a connection for liquid between the surge tank and main cylinder, a connection between the fluid pressure reservoir and the intensifier valve, a connection between the 25 pressure reservoir and surge tank through the pull-back valve, and an automatic check and positive relief valve interposed between the surge tank and the intensifier.

In testimony whereof, I have hereunto 30 set my hand this 9th day of July, 1917.

FERDINAND G. GASCHE.
